TELEPHONE SYSTEM

Henry Hovland, Williston Park, N. Y., assignor to
 Bell Telephone Laboratories, Incorporated,
 New York, N. Y., a corporation of New York

Application January 17, 1941, Serial No. 374,822

8 Claims. (Cl. 179—18)

This invention relates to telephone systems and more particularly to systems employing automatic switches for establishing conversational connections.

An object of this invention is to provide a more economical allotting arrangement of finder switches. Another object is to simplify the line-finder circuits by reducing the amount of electromagnetic apparatus required to a minimum without sacrificing any of the desirable operating features.

In accordance with this invention, the line finders of a group of finders are allocated sequentially by contact springs of off-normal switches associated with each finder, the normal contact springs thereof connecting the start circuit of a calling line to its own idle finder; and the off-normal contact springs, after the finder has operated, extending the start circuit for a subsequent calling line of the same group to the normal contact springs of a corresponding switch of another idle finder of the same group. Once a finder has operated, it cannot release immediately after a subscriber has disconnected but must remain in the actuated position until all finders in the group have functioned. The free finders then release and reoperate as required. However, should all finders of a group be engaged at any moment none can release, and a chain circuit connects the start circuit to another group of finders.

A feature of the invention resides in a line-finder circuit having a vertical off-normal switch in which contact springs are actuated by the initial vertical movement of the shaft and held in the actuated position until all finders of a group of finders are in the operated state.

Another feature resides in a line-finder circuit in which the vertical off-normal switch extends the common start circuit of a calling line to an idle finder switch of a group of finders and upon operation thereof passes the start circuit for a subsequent calling line to the next idle finder of the group. This sequence continues, the operated finders remaining in the operated position until all finders of the group have operated after which any disengaged finders is released.

A further feature resides in a telephone system having a plurality of groups of line finders wherein the finders of any group cannot release until all finders of said group have operated and wherein all finders of one group being engaged at one time, the start circuit for a subsequent calling line is extended to another group of finders.

Other features of the invention relate to circuit improvements which will be apparent from the following detailed description of the drawings comprising Figs. 1, 2 and 3, which show by means of the usual circuit diagrams a sufficient amount of apparatus to enable the invention to be described and understood.

The invention is illustrated in a system using step-by-step line-finder switches each having a capacity of two hundred lines, and each having two sets of wipers; but the invention is not limited in its application to the specific arrangement shown.

Referring to the drawings:

Fig. 1 shows schematically calling subscribers' stations A and B, placed in one group, corresponding line and start circuits, a chain circuit for transferring the start circuit from one group to another during an all-busy period of one group, a finder circuit, selector circuits, a connector, and a called subscriber's substation;

Fig. 2 shows the last finder of group 1 in skeleton outline; and

Fig. 3 shows the finders of group 2 in skeleton outline with the start circuit sequentially connected through the off-normal contact springs of the finder switches as embodied in this invention.

The subscribers' stations are of the type usually employed in automatic telephone systems and each includes a dial for use in obtaining connections with any other station. Each station connects at the exchange with a line circuit comprising a two-step combined line and cut-off relay, which actuates partially when the subscriber initiates a call and fully when the finder seizes the calling line. Each line circuit is assigned to a certain group and for illustration purposes substations A and B have been allotted to the same group, with subscriber A occupying the upper bank and subscriber B, the lower bank of the same level. The line-finder, selector, and connector switches are of the well-known two-motion step-by-step type.

In order to reduce the cost of the line-finder circuit, applicant has provided his line-finder circuit with a minimum of electromagnetic relays and he has accomplished this in general by the use of contacts on double-dog and vertical off-normal switches. In addition, the line-finder and change-over relays have been combined into a single two-step relay. Applicant's system is also arranged to prevent the release of any finder switch until all switches of a group have operated, thereby assuring continuity for a start cir-

cuit after it has been sequentially connected through the off-normal contact of an operated finder switch to the normal contact of a free finder switch.

The invention will be most readily understood from a detailed description of the operation.

Assuming a call to have been originated at subscriber's station A, a circuit is closed upon removal of the receiver, which energizes two-step combined line and cut-off relay 103 in its first step as follows: from ground through the lower winding of relay 103, back contact thereof, over conductor 101 through the substation loop, back over conductor 102, and thence through back contact and upper winding of relay 103 to battery. Two-step relay 103 operates in its first step to close the upper front contacts *a* and *b*, none of the normally closed contacts opening. At the uppermost front contact negative battery potential is connected from the middle winding of relay 103 in parallel to bank terminal 104 to mark the line of station A as calling and to the connector multiple; and at upper intermediate front contact connects ground to the No. 1 vertical bank contacts of commutator segments 128 of the same group and also completes a circuit by way of resistance 106 and common start conductor 120 through the winding of start relay 119 to battery. It will be noted that the vertical commutator bank 128 of one group of finders is slip multiplied in the customary manner to the vertical commutator bank 228 of the other group of finders.

Relay 119, upon energizing, at its right front contact provides an operating circuit for the combined finder start and change-over relay 123 by connecting ground through the left front contact of normally operated chain relay 121, thence through normal contact of VON switch 126, resistance 124, and to battery through the lower winding of relay 123. Relay 123 is also a two-step relay and upon energization in its first step closes the four contacts *c*, *d*, *e* and *f*. The uppermost front contact prepares a holding circuit for electropolarized relays 117 and 118 while the upper inner front contact prepares a holding circuit for relay 123 and also an operating circuit for the vertical and rotary magnets. Ground at the lower second intermediate front contact of relay 123 provides an obvious holding circuit for chain relay 121, which is normally held operated by ground at the lower normal contact of VON switch 126.

The closing of the lower first intermediate front springs of relay 123 provides a circuit from battery through winding of vertical stepping magnet 108, normal back contacts of relay 123, vertical magnet 108, and rotary magnet 109, respectively, thence through front contact of relay 123, normal contacts of 10th rotary step springs 127 and VON switch 126 and through left front contact of chain relay 121 and front contact of relay 119 to ground. Vertical magnet 108 operates and begins to step the shaft (not shown) and brushes of the finder LF up to the first level of the vertical commutator bank 128. However, magnet 108 attracts its own armature and thereby opens the circuit; but the shaft, while it is being elevated, causes the double-dog springs 116 to close and short-circuit the springs of the vertical magnet 108. The vertical magnet, therefore, remains energized until the shaft has taken a full step, after which the double dog drops into a ratchet (not shown) of the shaft, separates its springs 116 and thereby opens the circuit of vertical magnet 108. 75

Magnet 108 releases its armature, which recloses the above-traced circuit for another stepping operation. This automatic stepping continues to the level in which the calling line is found.

5 As soon as the shaft of the finder switch is moved out of its normal position, the VON switch 126 is actuated and thereby disconnects ground at its lower contact spring from chain relay 121. Relay 121, however, remains energized through 10 ground at relay 123 in an obvious circuit already mentioned. The actuation of VON switch 126 also prepares at its uppermost contact a circuit for release magnet 107 and at its intermediate contact transfers the previously mentioned start 15 circuit from the normal to the off-normal spring so that the operating circuit for relay 123 and magnet 108 becomes as follows: ground from right front contact of relay 119 through left front contact of relay 121, off-normal contact of VON 20 switch 126, front contact of relay 123, through upper back contacts of relays 117 and 118, and thence in parallel legs, one leg of the circuit continuing through lower front contact of relay 123, normal contact of 10th rotary step springs 127, 25 and through resistance 124 and lower winding of relay 123 to battery; and the other leg through contact of double-dog springs 116, lower back contact of relay 123 and winding of vertical stepping magnet 108 to battery. During the actuation 30 of the VON switch 126 neither vertical stepping magnet nor finder relay 123 releases as the off-normal spring of the switch makes before the normal spring breaks thus preserving continuity of the circuit.

35 When the level of the calling line is reached by the vertical switch (in this case it has been assumed as at the first level), ground on commutator segment 1 of vertical bank 128 is connected by vertical wiper 129, through upper winding of relay 123, normal back contact of release magnet 107, lower back contact of relay 123, thence through winding of vertical magnet 108 to battery. Vertical magnet 108 remains operated in this circuit until two-step relay 123 fully operates in its final step, after which relay 123 at its lowermost springs transfers the stepping operation from the vertical to the rotary phase, and at its upper two front contacts prepares operating circuits for relays 117 and 118. In fully operating relay 123 also provides itself with a locking circuit from battery through its lower winding and lower inner front contact, normal contact of 45 10th rotary step springs, lower front contact of relay 123, upper back contacts of relays 118 and 117, upper front contact of relay 123, off-normal contact of VON switch 126, left front contact of relay 121, and to ground through front contact of relay 119. Vertical magnet 108 releases and rotary magnet 109 operates in a circuit from battery through its own winding, lower front contact of relay 123, back contacts of vertical magnet 108 and rotary magnet 109, thence through upper back contacts of relays 118 and 117, upper front contact of relay 123, off-normal contact of 55 VON switch 126, left front contact of relay 121, and front contact of relay 119 to ground. As in the vertical stepping operation the double-dog switch contact 116 cooperates with the rotary magnet to advance the rotary brushes successively from one set of terminals to the next until the terminals of the dialing line are found.

When brush 105 makes contact with sleeve terminal 104 of the calling line, electropolarized relay 117 operates in a circuit from battery through the middle winding and upper front contact

of relay 103, sleeve terminal 104, brush 105, lower (primary) winding of relay 117, and through upper front contact or relay 123 to ground. This circuit is also effective to fully operate two-step combined line and cut-off relay 103. Relay 117 is so designed that when operated over the primary winding it will remain operated over the secondary or polarized winding in a circuit from battery through upper (secondary) winding of relay 117, lower back contact of relay 118, and thence through upper front contact of relay 123 to ground. The operation of relay 117 extends the tip and ring line conductors 101 and 102 through its upper front contacts to the associated selector circuit S; also causes the release of relay 123, and prevents further operation of rotary magnet 109 by opening the start conductor at its upper back contact. Relay 123, however, is slow in releasing and maintains a ground on the sleeve until ground has been returned from the selector circuit S. Ground from selector S provides a holding circuit for relay 117 over sleeve conductor 125, through lower inner back contact of relay 118 and upper (secondary) winding of relay 117 to battery. The call then proceeds through selector S—1 and connector C to the called substation L in the customary manner.

The combined line and cut-off relay 103, having fully operated, removes ground from the tip conductor 101 and battery from the ring conductor 102, and disconnects ground from the vertical commutator bank 128 and start conductor 120, thereby releasing start relay 119 for use with other calling subscribers of the same group such as subscriber B. Upon the release of relay 119 ground for relay 123 is removed but this has little effect on relay 123 as relay 117 has already opened the operating circuit for relay 123. With brush 105 in contact with sleeve terminal 104 of the line of substation A, the potential of the sleeve terminal of this line in the banks of all line finders and connector switches having access thereto will indicate that the line is busy and as a result will prevent any other hunting line finder or any connector switch from stepping on the terminals of this line.

No further operation takes place in the line-finder circuit until the connection is released by the calling subscriber at which time the selectors and connector through which the connection was completed are restored to normal, and the holding ground is disconnected from sleeve conductor 125. Combined line and cut-off relay 103 is thereby released so that another call may be initiated, or an incoming call received, at substation A. Relay 117 also releases when the holding ground is disconnected from sleeve conductor 125.

With the disconnection of a call between substations A and L the line-finder circuit LF would be free for another call under normal circumstances but the system shown herein does not permit the release of the finder switch until all finders of the group are in an operated position. When this condition is satisfied, chain relay 121 releases and connects operating ground for release magnet 107, which returns all free finder switches to normal, the engaged finders necessarily remaining in the operative position.

Let it be assumed, for example, that all line 70 finders of group 1 as shown in Figs. 1 and 2 are in use and that calling substation A, the last in the group, has just established his connection with selector S. As described earlier, relay 123 being a slow-release relay releases after ground 75

is connected from selector S over conductor 125 to provide a holding circuit for relay 117. After relay 123 releases, ground at its lower front contact is disconnected and opens an obvious operating circuit for chain relay 121. Previously with other free finders available operating ground for this chain relay has been obtained at the lower back contact of the VON switch 126 of a free finder. However, since all finders of the group are actuated and their associated VON switches are in off-normal positions, chain relay 121 releases and provides an operating circuit for release magnet 107 of every free finder. This circuit is traced from ground through the right back contact of relay 121, left back contact of magnet 107, uppermost contact of VON switch 126, thence through lower back contacts of relays 118 and 117 and winding of release magnet 107 to battery. Release magnet 107 operates and provides itself with a locking circuit from ground at its left front contact through the uppermost contact of VON switch 126, back contacts of relays 118 and 117 to battery through winding of magnet 107. Magnet 107 remains operated until the finder switch returns to normal after which the circuit is opened at the uppermost contact of VON switch 126. Magnet 107 having released and VON switches 126 of all free finders having returned to their normal positions, chain relay 121 reoperates in a circuit from ground at the lower back contact of a VON switch 126, through resistance 122 and winding of relay 121 to battery. Relay 121 thus places all free finders in readiness for succeeding calls.

35. The above example describes the condition where after all finders of a group had operated and the chain relay had released, free finders were available for further calls. Let it next be assumed that all finders of the group have operated and the chain relay has released but that no finder is free for any succeeding call. Assuming that a call is started at substation A, the combined line and cut-off relay 103 operates as described before and causes the start relay 119 to operate. Since chain relay 121 has released and cannot reoperate because of lack of free finders in its group, ground at the right front contact of relay 119 is transferred to the finders of group 2 through the outer left back contact of chain relay 121 over conductor 130, thence through the left front contact of chain relay 221 for group 2, normal contact of VON switch 226, resistance 224, to battery through winding of relay 223. Finder relay 223 operates 50 and repeats the operating procedure already described following the operation of relay 123 of group 1.

40. 55. What is claimed is:

1. In a telephone system, a group of lines, a group of finders having access to said lines, the finders of said group of finders arranged in sequence to serve said lines in a definite order, each of said finders having a set of switching contacts operable in response to the movement of the finders, a start circuit common to said finders, means including the switching contacts of the first idle finder in the group for extending said start circuit to said idle finder, means responsive to a call on one of said lines for closing said start circuit to operate said idle finder, the switching contacts of said operated finder serving to extend said start circuit to the next finder in the group, means for releasing said finders, and means for preventing the release of

an operated finder until all finders in the group are operated.

2. A telephone system according to claim 1, and means responsive to the operation of the last finder of said group for releasing all free finders to their normal positions.

3. In a telephone system, a group of subscribers' lines, a group of finders having access to said lines, the finders of said group of finders arranged in sequence to serve said lines in a definite order, each of said finders having an off-normal switch operable in response to the movement of the finder, a start circuit common to said finders, means including a normal contact of said switch of the first idle finder in the group for extending the start circuit to said idle finder, means responsive to a call on one of said lines for closing said start circuit to operate said idle finder, an off-normal contact on said switch of said operated finder serving to extend said start circuit to the next finder in the group, means including a relay and off-normal contact of said switch for releasing said finders, and means including a normal contact of said switch of a free finder in the group for preventing the release of an operated finder until all finders in the group are operated.

4. A telephone system according to claim 3, and means responsive to the operation of the last finder of said group for releasing all free finders to their normal positions.

5. A telephone system according to claim 3, and means including a relay responsive to the operation of the last finder of said group for releasing all free finders to their normal positions.

6. In a telephone system, a plurality of groups of subscribers' lines, a finder group for each of said groups of lines, the finders of each of said groups of finders arranged in sequence to serve said lines in a definite order, each of said finders having a set of switching contacts operable in response to the movement of the finder, a start circuit common to each of said finder groups, means including the switching contacts of the first idle finder in each of said groups for extending said start circuit to said idle finders, means responsive to a call in each of said subscriber line groups for closing said start circuit to operate said idle finders, the switching contacts of said operated finders serving to extend said start circuits to the next finder in their respective groups, means for releasing said finders, and means for preventing the release of the operated finders of any group until all finders in said group are operated.

7. A telephone system according to claim 6, and means responsive to the operation of the last finder of any group of finders for releasing all free finders in said group to their normal positions.

8. A telephone system according to claim 6, means responsive to the operation of the last finder of any group of finders for releasing all free finders in said group to their normal positions and also for transferring said start circuit from one group of finders having all finders engaged to another group of finders having free finders available for further service.
